CAN OPENER

Arthur Carp, Hillsdale, Mich.

Application May 5, 1948, Serial No. 25,110

5 Claims. (Cl. 30—15.5)

1

This invention relates to can openers of the type which comprise a friction wheel, arranged to engage the outer surface of the wall of a can adjacent the end thereof containing the disc-shape end wall which it is desired to sever, and a circular blade wheel adapted to penetrate the outer periphery of said disc-shape end wall to effect separation of the latter from the remainder of the can when relative rotary motion is caused to take place between the can and the can opener. The invention relates to can openers of this type in which the can opener itself is rotated around the can or in which the latter is rotated with respect to the can opener, the latter being held against rotary motion.

It is an object of the present invention to provide an improved can opener of the above described type in which the opener as a whole is readily engageable with a can, with the cutter wheel and the friction wheel correctly positioned relatively to one another and to the end wall portion of the can which it is desired to sever.

In order to effect the desired severing operation it is necessary that the cutter wheel should be held engaged with the can end wall in substantially tangential disposition relatively to the periphery thereof, or with the axis of rotation of the cutter disposed substantially radially with respect to the center of said end wall. In the available can openers, having the cutter and friction wheels mounted upon pivotally connected hand lever members, there is a tendency for the cutter wheel, and hence the friction wheel, to assume an askew position relatively to the periphery of the can end as the lever carrying the friction wheel is closed upon the other lever carrying the cutter wheel. As a result the cutter and friction wheels are improperly positioned and if any cutting action at all takes place this tends to be in a direction outwardly away from the periphery of the can instead of in the direction thereof.

An object of the invention therefor is to provide a can opener of the type described in which one, or both lever members, carry a member adapted to be positioned immediately adjacent one side of the cutter wheel and in engagement with the periphery of the can so as to oppose any tendency for the cutter wheel to assume an askew position and to constrain the wheel to take up the substantially tangential position as above mentioned and this without any conscious effort on the part of the operator.

A further object of the invention is to provide a can opener of the type described in which the

lever member carrying the friction wheel has sufficient inherent resiliency as to compensate for varying thicknesses both depthwise and radially of the can. Accordingly, the opener is capable of adjustment automatically to variations in the depth of the peripheral bead beneath which the friction wheel engages (such bead being defined on the can around the periphery of the disc-shape end wall thereof penetrated by the cutter wheel) as well as to radial variations in the can wall presented, for instance, at the longitudinal seam normally present on the cans.

Another object of the invention is to provide a can opener of the type described in which provision is made for the ready effecting of radial adjustment of the lever members relatively to each other so as to compensate for wear on the cutter and/or friction wheels in prolonged use of the can opener.

Yet another object of the invention is to provide a can opener of the type described with parts thereof formed to permit the opener to be employed to remove crown corks or to punch out a pouring opening in an end wall of the can, whereby the can opener combines the three functions of a can opener proper, a crown cork remover and a can puncturing tool.

Still a further object of the invention is to provide a can opener of the kind described in which one of the lever members carries a pivotally mounted arm adapted, in its closed position, to function to centralize or correctly position the cutter wheel in its cutting position on a can and, in its opened-out position, to function as a crown cork remover.

Yet a further object of the invention is to provide a can opener of the kind described which is adaptable for use as a wall type can opener, that is, an opener, which is held stationary while the can is rotated to sever its end wall or which can be manipulated by hand to cause the opener to rotate around the can, the opener having a novel handle construction which permits the required rotary motion to be effected for either use of the opener.

A further object of the invention is to provide a can opener of the kind specified in which the lever member carrying the cutting wheel has a roller member adapted for guiding contact with the peripheral can bead as the cutting operation proceeds.

These objects and advantages, resulting from the combination construction and arrangements of parts, will appear clear from a consideration of the following detail description of several prac-

tical embodiments of the invention given by way of example with reference to the accompanying drawings in which:

Fig. I is a front elevational view of one embodiment of the invention, with the hand lever members shown opened-out and the positioning lever arm on the cutter carrying lever member in its normal position.

Fig. II is a similar view to Fig. I but showing the can opener applied to a can and the positioning lever arm swung over into its operative position prior to the closing of the lever member carrying the friction wheel.

Fig. III is a similar view to Fig. II but showing the friction wheel lever member in the closed position and the positioning lever arm returned to its normal vertical position.

Fig. IV is a rear elevational view of Fig. I.

Fig. V is a perspective view of this embodiment of the invention in use as a crown cork remover.

Fig. VI is a fragmentary perspective view of the same can opener in use as a can end wall puncher, preparatory to the actual punching operation.

Fig. VII is a similar view to Fig. VI but showing the entire can opener and the punching operation completed.

Fig. VIII is an end view of Fig. III.

Fig. IX is a front elevational view of another embodiment of the can opener in accordance with the invention, employing a dual function lever arm on the cutter wheel carrying lever member, the can opener being shown in the closed and operative position and the dotted line position of said dual function lever arm denoting the alternative position of this arm when employed to remove crown corks.

Fig. X is a view similar to Fig. IX but showing the lever member carrying the friction wheel swung into the open position.

Fig. XI is a front elevational view of a further embodiment of the can opener in accordance with the invention shown in operative position for use as a wall type opener.

Fig. XII is a similar view to Fig. XI but showing the can opener dismantled from the wall bracket and the lever member carrying the friction wheel swung into the open position.

Fig. XIII is a longitudinal section on the line A—A of Fig. XI.

Fig. XIV is a side elevational view of yet another embodiment of the invention with the opener shown in the closed operative position.

Fig. XV is a similar view to Fig. XIV but showing the lever carrying the friction wheel swung into the open position, and

Fig. XVI is a longitudinal view on the line B—B of Fig. XIV.

Referring to the drawings and first to Figs. I to VIII a can opener is provided comprising a pair of hand lever members 1 and 2 pivotally connected together near one end thereof, by a screw stud 3 and tightening nut 4, for opening and closing swinging movement of the lever members relatively to one another.

The lever member 1 is formed with a lateral extension 1a, with which the screw stud 3 is associated, and which extension has a transverse short rotatable spindle 5 carrying, on one side of the extension 1a, the friction wheel 6 and, on the opposite side, the handle 7 by which the spindle, and hence the friction wheel, are rotated.

The other hand lever 2 carries the cutter wheel 8, freely rotatable upon a screw stud 9 secured upon this lever member by the nut 9a (Fig. IV) so that in the closed position of the two lever

members the friction wheel and the cutter wheel are brought diametrically opposite one another, as shown in Figs. III, V and VIII, with the adjacent peripheral portions thereof in overlapping but laterally spaced relationship.

The two hand lever members are of cranked formation, as seen in Fig. V, and the friction and cutter wheels are so located upon their respective lever members that with the can opener positioned upon a can 10 the mutually related lever portion 1a and 2a extend substantially longitudinally with respect to the outside of the can wall, whereas the other mutually related lever portions 1b and 2b extend at a slight angle above the can end wall 10a which it is desired to remove and in a direction towards the center of said end wall. The cutter wheel spindle 9 is perpendicular to its lever portion 2b whereby the cutter wheel assumes a correspondingly inclined position with respect to the inner side wall of the peripheral can bead 10b, whereas in the closed condition of the lever members the friction wheel is disposed in a plane substantially parallel with the can wall 10, with its serrated peripheral edge 6a engaged beneath outside lower edge 10c of this bead.

The cutter wheel is formed with an annular groove 8a (Figs. V, VII and VIII) into which the can bead enters, much in the same way as is disclosed in my co-pending application, Serial No. 597,177, filed June 2, 1945, but whereas in that application this annular groove is of V cross section I now prefer that the rear wall 8b (Fig. VIII) of the annular groove should be perpendicular to the spindle 9 and that the base of the groove should be constituted by a short cylindrical portion 8c.

A projecting lip 12, bent perpendicularly from the lever member part 1a serves, in the conventional manner, to hold the lower end of this lever member part, and hence its companion part 2a of the other lever member, spaced somewhat from the outer surface of the can wall, in the applied condition of the can opener.

The lever portion 1a is formed with a transverse slot 13 open at one end to the free edge 1c of this lever portion and imparting to the latter the possibility of a cantilever action about the closed end 13a whereby the portion 14 carrying the friction wheel is able to bend about this pivot end to contract or open the slot end portion 13b to compensate for variations in the depth of the bead 10b as the can and opener are rotated relatively to one another, with the opener in operative position on the can.

Automatic compensation is also given to variations in the radial direction of the can by the free end portion of the said lever part 14 being bent back slightly from the companion part 2a of the other lever member to form a gap 15 between the two, as shown in Fig. VIII, and thereby permit this edge portion of the lever portion 14 to partake of a radial flexing movement relatively to the can and thereby maintain the friction wheel in correct engagement with the underneath edge surface of the can bead 10b.

Angular movement of the two lever members is permitted by the rear boss portion of the spindle 5 carrying the handle 7, being guided within a transverse arcuate form slot 15 in the lever portion 2a.

In order correctly to position the cutter wheel 8 with respect to the inside of the peripheral can bead 10b the lever portion 2b has a lever

arm 16 pivotally mounted on its front face, by a screw stud 17 and nut 18, which lever arm is formed with a ledge 16a at its lower end (assuming the can opener and can to be vertically disposed) and terminates at one end of the ledge, adjacent the cutter wheel 8, in a downwardly directed shallow lip 16b. This lever arm 16 is capable of being readily tripped about its pivot 17 to bring its depending lip portion 16b to exert pressure upon the top can end wall 10a immediately adjacent one side of the cutter wheel 8 with the ledge 16a overlying the corresponding portion of the peripheral can bead 10b.

The outside longitudinal edge of the lever arm 16 is bent back, in its upper portion, to form a ledge 16c, which, when the lever arm is swung back into the position shown in Fig. II, has abutting engagement with the edge portion 19 of the lever portion 2b so as thereby to limit the swinging movement in this direction. Engagement of the lower end of this ledge 16c with the transverse edge portion 20 of the lever portion 2b arrests the return swinging movement of this lever arm to thereby locate the latter normally in a vertical position as seen in Figs. I and III.

Normally, this lever arm is in the vertical position, as seen in Figs. I and III.

With the parts as seen in Fig. I, the can opener is capable of being applied to a can with a portion of the can bead 10b located within the annular groove 8a of the cutter wheel and the friction wheel 6 positioned just clear of the can wall 10. With the operator's hands applying a steady-ing action to the can opener, the lever arm 16 is then tripped into the position shown in Fig. II to cause the depending lip 16b to exert pressure upon the top of the can end wall which it is desired to sever and this immediately adjacent to one side of the cutter wheel 8. This has the effect of temporarily locking the can opener upon the top of the can and of so positioning the cutter wheel that when the lever member 1 is closed upon the other lever member 2 and in so doing the lever arm 16 is automatically tripped back into its vertical position, as seen in Fig. III, not only will the cutter wheel penetrate the top of the can while correctly positioned thereon but the friction wheel 6 will also be correctly located in substantially diametric relationship with respect to the cutter wheel, with its serrated edge 6a in contact with the bottom of the bead 10b.

The completion of the severing operation can then be effected with the engagement of the lever arm ledge 16a and depending lip 16b with the top of the can opposing any tendency for the friction wheel, during the cutting operation, tending to lift the cutter wheel out of the can.

Longitudinal adjustment of the two lever members 1 and 2 relatively to one another, to compensate for wear of the cutter and friction wheels, or for other reasons, is possible by the provision of the lever member 2 with an elongated slot 21 through which the corresponding portion of the screw stud 3 passes. Thus, by loosening the nut 4 it is possible to adjust the two lever members relatively to each other within the limits of this slot 21 and thereafter tighten the nut 4. An eccentric washer 22 located upon the stud 3 between the nut 4 and the adjacent surface of the lever member portion 2a and engageable with an abutment ledge 23 on the lower edge of this portion 2a ensures that there shall be no longitudinal slipping movement between the two lever members, in the tightened condition of the nut 4, due to the existence of this slot 21. This ec-

centric washer is turned about the stud 3, to correspond with adjusted positions of the stud within the slot, so as to ensure that the periphery of the washer has engagement with the ledge 23.

The can opener as shown in Figs. I to VIII is also formed so as to be capable of being used as a crown cork remover, as shown in Fig. V, or as a can puncher, as shown in Figs. VI and VII.

To this end the handle end of the lever member 2 is formed with a finger portion 24 which is bent back from the portion 2b and terminates in a lip 24a which is laterally spaced from the overlying lever member portion 25 to permit this lip to be engaged with the peripheral flange 26b of a crown cork 26 with the can opener held bodily, as shown in Fig. V, and with the portion 25 engaging over the top of the crown cork, the side flange portion 27 of the lever portion 2b having a guiding influence against the fluted crown cork flange 26b in angularly spaced relationship to the lip 24a.

To permit the can opener to be employed as a can puncher the lower end of the lever member 1 is formed with a spike portion 28 of acute angle formation, as shown particularly in Figs. V and VI, and with a transversely bent lip portion 29 which extends in a plane perpendicular to the plane of the spike portion 28, the latter have sharp edges.

To employ the can opener to punch a triangular hole 30 (Fig. VII) in the can end wall 10c the opener is held bodily in one hand with the spike portion 28 overlying the can end wall and extending from the can bead 10b with the can opener held against the can wall 10 by the abutment of the lip portion 29 with the latter. While so held against the can the opener as a whole is capable of levering about the abutment 29 to cause the spike portion 28 to press down upon the can end wall 10c. In so doing the spiked end portion will puncture the end wall 10c to form the triangular hole 30.

Referring now to the modified construction of can opener shown in Figs. IX and X, wherein like parts to those in the previous figures have been given the same reference numerals, instead of the lever arm 16 this construction is provided with a dual function lever arm 31, pivoted upon the handle end of the lever member 2, by means of the pivot stud 32, and formed generally of angular section to provide a front flange 33 and a side flange 34. The front flange portion 33 is severed to provide two longitudinally spaced lip portions 35 and 36 of which the lip portion 35 is bent forwardly out of the plane of the flange 33 and in the closed-in condition of the lever arm 31, as shown in full lines in Fig. IX, extends immediately adjacent one side of the cutter wheel 8, whereas the other lip portion 36 extends generally in the plane of the flange portion 33 and the cutter wheel but is formed so that its corner portion 36a is slightly spaced behind the periphery of the cutter 8 in the fully closed condition of this lever arm. Thus, in this closed condition the lip portion 36 functions to hold the cutter wheel 8 correctly positioned upon the can 10 and such positioning is assisted by another laterally projecting lip portion 38 formed at the top edge of the slot 15 (for accommodating the angular movement of the friction wheel 6) and located immediately adjacent the opposite side of the cutter wheel so as to overlie the peripheral can bead 10b in the applied condition of the can opener. When closed upon the lever member 2 the lever arm 31 abuts the latter by its side flange

34, the latter affording a comfortable gripping surface for the bent fingers of the operator's clenched hand. The one function of this lever arm 31, therefore, is to enable the can opener to be applied to a can with the cutter and friction wheels correctly positioned thereon. The other function of this lever arm is to permit the can opener to be employed as a crown cork remover. To this end the free end of the lever arm terminates in a lip 37, which is bent in the opposite direction to the lip portion 35, and the transverse edge 35a of the latter is formed with one or more nicks 35b. It will be seen therefore, from examination of Figs. IX and X, that a recess is formed at the free end of this lever arm, this recess being defined on two sides by the edge 35a and the adjacent edge 37a of the lip 37 and having its base defined by the lip 36, which latter extends generally perpendicularly with respect to the lip portions 35 and 37.

To employ the can opener as a crown cork remover, the lever arm 31 is swung into the opened-out position as shown in dotted lines in Fig. IX. When so positioned the lever arm can be positioned with respect to a crown cork, which it is desired to remove, so that a peripheral portion of the crown cork flange is accommodated within said recess with the lower peripheral edge of the crown cork engaged in one of said nicks 35b, and the terminal lip 37 positioned to bear over the top of the crown cork with its edge 37a engaged with the latter. The normal lever action can then be exerted through the lever arm 31 to remove the crown cork.

The can opener construction shown in Figs. XI, XII and XIII also has parts similar to those of the previously described constructions and denoted by the same reference numerals, but the present can opener construction is designed for use either as a hand held can opener, with the latter rotated around the can or as a wall-type opener, with the latter held stationary and the can rotated. This alternative use of the can opener is possible by the hand lever member being formed at its lower end with a depending tongue 39 of taper formation, as shown, and which is engageable within a correspondingly formed socket 40 of a wall bracket 41. In the modified construction of can opener also, the means for correctly positioning the cutter wheel for its cutting operation consists of the lip projection 38, for engaging over the peripheral can bead immediately adjacent one side of the cutter wheel, and of a lever arm for providing engagement with the top of the can on the opposite side of the cutter wheel. This lever arm, in the present construction is indicated at 41 and is pivoted at the lower end of the lever member 2, by the stud 42. The lever arm 41, therefore, is swung upwardly into its operative position, as shown in Figs. XI and XII, where a pointed lip portion enters behind the periphery of the cutter wheel 8 to engage the can and assist the lip 38 in correctly positioning the cutter for its desired cutting operation.

To permit the friction wheel 6 to be rotated with the can opener mounted upon the wall bracket 41 or held in the operator's hand, a novel handle construction is employed, as shown particularly in Fig. XIII where the handle 7 has one wing arm 7a thereof extended and fitted at its free end with a knob 7c by which the handle is actuated when the can opener is employed in association with a wall bracket. The handle construction is such that the central handle por-

tion 7d can be engaged by the operator to rotate the friction wheel 6 when the can opener is hand held.

Referring now to the can opener construction shown in Figs. XIV, XV and XVI, again the same reference numerals have been employed to denote parts corresponding to the previously described constructions, but in the present construction the lever arm 16, 31 or 41 has been dispensed with and reliance placed upon an angularly set roller member 44, carried upon the lever member 2 and engageable over the peripheral can bead 10b to assist in maintaining the correct engagement of the cutter wheel 8 with the can. This roller member is conveniently formed with a knurled or roughened surface as shown for maintaining the desired rolling, yet gripping, engagement with the bead 10b.

In this modified can opener construction the lever member 1 has the slot portions 13, 13b giving the possibility of a cantilever action, which latter, however, is further enhanced by the provision of yet another transversely extending slot 45 defining, with the slot 13, an intermediate web portion 46 of the lever member 1 upon which the pivot pin 47 for the two lever members 1 and 2 is mounted.

This pivot is formed by a screw stud, shown clearly in Fig. XVI, which stud is secured in position by a nut 48 and has a portion 47a locatable within an elongated slot 49 in the lever member portion 46. This slot permits relative longitudinal adjustment movement of the portion 46 and the lever member 2 to take place automatically with the swinging movement of the lever member 1 into the closed position and with the can opener applied to a can. Such automatic adjustment motion ensures that the friction wheel 6 is maintained in efficient gripping engagement with the can bead 10b as the wheel is made to traverse the latter. The said motion is permitted not only by the existence of the slot 49 but also by the camming of the eccentric washer 50 over the lip 51 at the lower end of the lever member 2, as the lever member 1 is swung into the closed position and by the engagement of the roller sleeve 52 with the bottom lip 53 on the lever member portion 1a. The eccentric washer 50 is carried upon a screw stud 54 secured in position by a nut 55 and passed through an elongated slot 56 in the lever member portion 2a.

It is desired to point out that one important advantage of the cutter constrictions according to the invention is that a simple plier-like closing action, capable of being performed by grasping the cutter in one hand, is all that is needed to bring the cutter into operative position upon a can, which position is positively maintained by rotation of the friction wheel in the can cutting direction, rotation in the opposite direction serving automatically to produce an opening movement of the cutter.

Having thus described in detail the several features of my invention by reference to several practical embodiments thereof, what I claim as novel and wish to cover by Letters Patent is as follows:

1. A can opener comprising a lever member, a cutter wheel rotatably mounted upon said lever member, another lever member, a friction wheel rotatably mounted upon said second mentioned lever member, means pivotally connecting said lever members towards one end thereof while permitting relative longitudinal movement of

said members to adjust the mutually engaging operative position of said cutter and friction wheels, the latter being mounted upon their respective lever members intermediate said pivotal connection and the free ends of the lever members and being so located that peripheral portions thereof overlap one another in clamp forming spaced relationship in the closed condition of the lever members, whereby it is possible to grip the peripheral edge portion of a can between the two wheels, a handle member for rotating one said wheel, a separate lever member, means pivotally mounting said separate lever member upon the lever carrying said cutting wheel in spaced relation to one side of the latter, said separate lever member being formed and located to exert pressure against the top of a can to which the opener is applied, whereby to position the cutting wheel and the friction wheel for their required operations.

2. A can opener as claimed in claim 1 said separate lever arm being formed with a depending lip portion engageable, immediately adjacent one side of the cutter wheel, with the outer peripheral portion of the can end wall to be severed, when the separate lever arm is swung into one position, and being formed also with a ledge portion engageable over the top edge of the peripheral can bead.

3. A can opener as claimed in claim 2 wherein said separate lever arm is pivoted upon the cutter carrying lever member in position to be automatically tripped upon a closing movement of the other lever member carrying the friction wheel.

4. A can opener comprising a pair of lever members, means pivotally connecting the lever members together, a cutter wheel rotatably mounted upon one said lever member and a friction wheel rotatably mounted upon the other said lever member, said cutter wheel and friction wheel being so positioned upon their respective lever members as to co-act with a can, for the severing of an end wall thereof, in the closed condition of the lever members with the

conventional can bead held between overlapping peripheral portions of the cutter wheel and friction wheel, said pivotal connection means being engaged with an intermediate portion of the lever member carrying the friction wheel, which portion is partially severed from the remainder of this lever member by transversely extending slots imparting the possibility of a double cantilever action to said intermediate lever portion.

5. A can opener comprising a pair of hand lever members, means pivotally connecting said lever members together, a cutter wheel rotatably mounted upon one said lever member and a friction wheel rotatably mounted upon the other said lever member, said cutter wheel and friction wheel being so positioned upon their respective lever members as to co-act with the inner periphery and the bottom edge of the conventional peripheral bead at one end of a can in the can applied condition of the can opener, and the said friction wheel being mounted upon a portion of its lever member which is partially severed from the remainder of this lever member by a transverse slot in this member, whereby the said lever member portion has the possibility of a cantilever action in a direction transverse to the rotational axis of the friction wheel and the said cantilever member portion being also formed to have a certain degree of resiliency in the direction of said rotational axis, whereby the friction wheel is permitted to partake automatically of adjustments in position to compensate for variations in the can bead both depthwise and radially with respect to the bead.
